UNITED STATES PATENT OFFICE.

HERBERT FREDERICK HENRY SHIELDS, OF WELLING, ENGLAND, ASSIGNOR OF ONE-HALF TO THE BRITISH ROPEWAY ENGINEERING COMPANY, LIMITED, OF LONDON, ENGLAND, A BRITISH COMPANY.

AERIAL ROPEWAY ON THE SINGLE-ROPE SYSTEM AND THE LIKE.

1,386,282.

Specification of Letters Patent. Patented Aug. 2, 1921.

Application filed February 28, 1921. Serial No. 448,463.

To all whom it may concern:

Be it known that I, HERBERT FREDERICK HENRY SHIELDS, a subject of the King of England, residing at Welling, in the county 5 of Kent, England, have invented certain new and useful Improvements in Aerial Ropeways on the Single-Rope System, and the like, of which the following is a specification.

10 This invention relates mainly to aerial ropeways on the single-rope system, and particularly to boxheads or carriers for use thereon. It is also applicable to rope-driven runways.

15 In aerial ropeways on the double-rope system the usual grip for attachment to the usual hauling rope for hauling the load along the ropeway has heretofore been used for hauling the load along shunt rails at 20 stations. One such grip known as the over-type lever grip comprised two jaws, whereof one was fixed on the boxhead and arranged to be opened and closed by means of actuating rails provided at the stations.

25 In aerial ropeways on the single-rope system the main hauling rope is not available for hauling the boxheads along the shunt rails at stations, and it has been customary heretofore to push the loads by hand along 30 the shunt rails or to use a chain drive which, however, had the defect that it could be used only along straight lines and not around curves.

35 This invention has for its main object to apply the advantages of mechanical traction of the load on the shunt rails at stations to aerial ropeways on the single-rope system.

40 Another object is to provide an improved construction of boxheads for the single-rope system of aerial ropeways and a simpler form of carriage for rope-driven runways such that they can be automatically attached to an endless moving rope and be maintained 45 in attachment therewith under the action of gravity.

45 According to this invention there is provided in an aerial ropeway on the single-rope system or a rope-driven runway comprising a traveling boxhead, the combination with a shunt rail, of a shunt traction rope which is also operated on the single-rope system and is supported in line, or approximately in line, with the shunt rail,

and gripping means on the boxhead operated by contact with the shunt rail for gripping the boxhead to the traction rope. 55

According to another feature of the invention, the said gripping means comprise a movable jaw and a load-carrying wheel 60 that is operatively connected therewith and is arranged to run on the shunt rail, so that when the boxhead arrives at a station the gripping means is automatically closed upon the traction rope and thereupon maintained 65 in attachment therewith under the action of gravity while the boxhead travels along the shunt rail.

The aforesaid load-carrying wheel is preferably carried directly by the movable jaw 70 for the purpose of diminishing the cost of manufacture.

Other features of the invention will be described hereinafter and pointed out in the claims. 75

The invention is diagrammatically illustrated by way of example in the accompanying drawing wherein:

Figure 1 is an end elevation showing one form of improved boxhead according to the 80 invention provided with an overtype auxiliary gripping device which is shown open;

Fig. 2 is a like view of the boxhead with the auxiliary gripping device shown closed, on an auxiliary traction rope at a station, 85 and

Fig. 3 is a side elevation of the boxhead on a shunt rail according to Fig. 2;

Figs. 4 and 5 are end elevations of a boxhead provided with a lateral downwardly 90 directed auxiliary gripping device, showing the same open and closed respectively;

Figs. 6 and 7 are end elevations showing a boxhead having a modified overtype grip in its open and closed positions respectively, 95 and

Figs. 8 and 9 are end elevations of a boxhead having another form of overtype grip shown in its open and closed position, respectively. 100

Like reference letters designate like parts throughout the several views.

Referring first to Figs. 1 to 3, a boxhead A of a construction as usually employed in an aerial ropeway on the single-rope system 105 and having the usual offset wheels B for running on the usual shunt rails, whereof one is indicated at C, has in addition to the

usual main grips D for the main ropeway cable E, additional gripping means designated generally by the letter F for gripping an auxiliary traction rope G at a station. This additional gripping means is a lever grip of the overtype comprising a fixed jaw F¹ mounted on the frame of the boxhead, and a movable jaw F² pivoted on the fixed jaw. If desired, the jaw F² may, however, be pivoted on the said frame. The movable jaw has an arm bent in the form of a bell-crank lever, whereof the longer arm F³ extends outward transversely of the boxhead on the opposite side from the hanger H of the bucket, and the shorter arm F⁴ extends downward to about the level of the upper end of the bucket-hanger. Pivotally mounted on the lower end of the shorter arm F⁴ which, as shown in Fig. 3, spreads 20 out lengthwise of the boxhead to beyond the axes of the wheels B, are two additional shunt-rail wheels J which, when the gripping device F is open, are tilted at an angle to the vertical as shown in Fig. 1, but are vertical or approximately so when the gripping device is closed, as shown in Fig. 2. The wheels J and the wheels B are preferably at equal distances apart as shown, but if desired the wheels J may be farther apart or closer together than are the wheels B. Also, only one wheel J may be provided, but in this case it will be situated in the middle of the boxhead.

A station in an aerial ropeway on the single-rope system at which above described additional rope-gripping device is to be used for mechanically hauling the boxheads will be provided with an additional shunt rail K in such a position that on a boxhead 35 arriving at the station, the additional shunt-rail wheels J will ride on to it and take up at least a part of the load. The traction rope G guided by sheaves, such as L, is lighter than and is provided as an auxiliary to the main hauling rope E, is supported in line or approximately in line with the shunt-rail K, and is operated on the single-rope system. Further, it is mounted in such a 40 position that it is automatically gripped by the auxiliary gripping device F on the boxhead when the shunt-rail wheels J run on to the shunt rail K which thus operates to close the movable jaw F². On the main clips D being detached from the main hauling rope 45 E, the whole of the load will be supported by the additional shunt-rail wheels J and will operate to keep the described overtype lever grip F, closed on the traction rope G.

Should it be desired at any time to 50 lease the traction rope G while the boxhead is being hauled along the station shunt-rail K, the normal running wheels B will be taken by a shunt-rail such as C, whereupon the wheels J will become unsupported and 55 fall away, thus opening the auxiliary grip F.

In the modification shown in Figs. 4 and 5, an arm F⁵ that extends horizontally outwardly from the boxhead A away from the hanger H at right-angles to its direction of travel has a downwardly-directed jaw F⁶ 70 formed on its outer end, and a downwardly-directed movable jaw F⁷ is pivoted on the fixed jaw and has an angular arm F⁸ that carries the shunt-rail wheels J. It will be appreciated that when these wheels run on 75 the shunt-rail K provided for them, the lever grip F⁷, F⁸ can grip an auxiliary traction rope G arranged at the station in line or approximately in line with the rail K.

Instead of the operative arm F³ of the 80 movable jaw being directed away from the bucket-hanger as shown in Figs. 1 to 3, it may be directed toward the same as in the modified construction shown in Figs. 6 and 7. In this arrangement no additional 85 wheels such as J are provided, but the usual running wheels B are carried on the arm F³ having the movable jaw, and the usual shunt rail C is used for actuating the auxiliary grip, the operation being otherwise the same 90 as described above with reference to Figs. 1 to 3.

Figs. 8 and 9 show another modification similar to that shown in Figs. 6 and 7, but in which the wheels B that actuate the movable jaw F² are arranged to move vertically instead of to swing about a pivot. As clearly shown, the member in which the wheels B are journaled is pivotally connected at M to a short arm F⁹ integral with 100 the movable jaw F², and carries a pin N that is movable up and down in a vertical slot A² provided in the side of the frame of the boxhead.

It will be appreciated that the provision 105 of an auxiliary traction rope running on the single-rope system at a station and arranged to be gripped by an auxiliary gripping device provided on the boxheads results in the advantage of mechanical haulage of the double-rope system of aerial rope-ways being applied at stations to ropeways on the single-rope system. As indicated in broken lines in Fig. 2, sheaves L can be arranged in various positions for guiding the 110 auxiliary traction rope G as required.

When the invention is applied to a rope-driven runway, wherein a moving rope is used for hauling carriers along a track in the form of a rail, the described load-carrying auxiliary grip may be the sole grip on the carrier, and the rope usually provided for operating such runways will constitute the traction rope G operated on the single-rope system. It is to be understood, therefore, that the term "shunt-rail" and "shunt" or "auxiliary" traction rope used in this specification and in the claims include, respectively, the moving rope of a runway, and the track of a runway.

It will be appreciated that various modifications may be made without departing from the scope of the invention as defined in the claims. For example, auxiliary grips

5 of forms other than that described may be employed, such as a screw grip, or a grip of the inclined plane type. These grips are of known types in ropeways on the double-rope system and a person versed in
 10 the art will be readily able to adapt them to a boxhead to be operated in a manner analogous to that described above with reference to a grip of the lever type. Whatever type of grip is employed, however, it
 15 is essential that the movable jaw shall be operated under the action of a part, or the whole, of the load when the boxhead carrying the load is to be attached by means of the grip to an auxiliary traction rope at a
 20 station, and that the said attachment shall be maintained under the action of the load.

What I claim as my invention and desire to secure by Letters Patent is:

1. In a monocable or single-rope trans-
 25 portation plant, the combination of a rail, a boxhead supported by and arranged to travel along the same, a traction rope operated on the single-rope system and supported in positional relation to said rail,
 30 and gripping means on the boxhead operated by contact with said rail and arranged to grip said rope.

2. In a monocable or single-rope trans-
 35 portation plant, the combination of a shunt-rail, a boxhead supported thereon, a shunt traction-rope operated on the single-rope system and supported in positional relation to said rail, and gripping means on the boxhead operated by contact with said rail and ar-
 40 ranged to grip said rope.

3. In a monocable or single-rope trans-
 45 portation plant, the combination with a shunt-rail, of a shunt traction-rope operated on the single-rope system and supported in posi-
 tional relation to the rail, a boxhead having a grip comprising a fixed jaw and a movable jaw arranged to grip said rope, and a load-
 50 carrying wheel operatively connected with the movable jaw and arranged to run on said shunt-rail.

4. In a monocable or single-rope trans-
 55 portation plant, the combination with a shunt-rail, of a shunt traction-rope operated on the single-rope system and supported in posi-
 tional relation to the rail, a boxhead having a lever-grip arranged to grip said rope, said grip comprising a jaw fixed on the boxhead, and a movable jaw pivoted on the boxhead, which movable jaw has a bent arm directed

at right-angles to the direction of travel of 60 the boxhead, and a load-carrying wheel jour-
 naled in said bent arm and arranged to run on said shunt-rail.

5. In a monocable or single-rope trans-
 65 portation plant, the combination with a shunt-
 rail, of a shunt traction-rope operated on the single-rope system and supported in posi-
 tional relation to the rail, a boxhead having a bucket-hanger pivotally mounted in and depending at one side from the box-
 70 head, said boxhead having a lever-grip ar-
 ranged to grip said rope, said grip comprising a jaw fixed on the boxhead, and a move-
 able jaw pivoted on the boxhead, which move-
 able jaw has a bent arm directed at right-
 75 angles to the direction and travel of the box-
 head toward said hanger, and a wheel for
 supporting the boxhead and its load jour-
 naled in said bent arm, said wheel being situ-
 ated in a vertical plane between a depending 80 portion of the hanger and the adjacent side
 of the boxhead and being arranged to run on said shunt-rail.

6. The combination, with a boxhead for
 85 use in a transportation plant operated on the single-rope system, which boxhead has a grip situated in its central longitudinal plane for attachment to the rope, of an aux-
 iliary grip for attachment to a shunt-rope
 90 also operating on the single-rope system, which auxiliary grip comprises a jaw fixed on the boxhead, a movable jaw pivotally mounted on the boxhead and having an arm directed at right-angles to the direction of travel of the boxhead, and a wheel for sup-
 95 porting the boxhead on a shunt-rail, which wheel is operatively connected with said arm.

7. The combination, with a boxhead for
 100 use in a transportation plant operated on the single-rope system, which boxhead has a piv-
 otally mounted bucket-hanger depending at one side therefrom, and a grip situated in its central longitudinal plane for attachment to the supporting rope, of an auxiliary grip for
 105 attachment to a shunt traction-rope also operating on the single-rope system, which auxiliary grip comprises a jaw fixed on the boxhead, and a movable jaw pivotally mounted on the boxhead and having an arm directed at right-angles to the direction of travel of the boxhead toward said hanger, which arm has at its outer end a down-
 110 wardly-directed portion, and a wheel jour-
 naled in said downwardly-directed portion 115 for supporting the boxhead on a shunt-rail.

In testimony whereof I affix my signature.
 HERBERT FREDERICK HENRY SHIELDS.
